ATTORNEY,

UNITED STATES PATENT OFFICE.

WILLIAM H. H. BRUNTON, OF ELK CITY, KANSAS.

GRAIN WEIGHING AND REGISTERING MACHINE.

SPECIFICATION forming part of Letters Patent No. 397,628, dated February 12, 1889.

Application filed May 1, 1888. Serial No. 272,407. (No model.)

To all whom it may concern:

Be it known that I, WILLIAM H. H. BRUNTON, of Elk City, in the county of Montgomery and State of Kansas, have invented a new and Improved Grain Measuring and Registering Machine, of which the following is a full, clear, and exact description.

The object of the invention is to provide a new and improved machine for automatically measuring and registering the grain delivered by an elevator connected with a thrashing-machine or grain-bin.

The invention consists of certain parts and details and combinations of the same, as will be fully described hereinafter, and then pointed out in the claims.

Reference is to be had to the accompanying drawings, forming a part of this specification, in which similar letters of reference indicate corresponding parts in all the figures.

Figure 1 is a front elevation of the improvement. Fig. 2 is a cross-section of the same on the line $\alpha\alpha$ of Fig. 1. Fig. 3 is a longitudinal sectional elevation of the improvement on the line yy of Fig. 2. Fig. 4 is a sectional plan view of the same on the line zz of Fig. 1. Fig. 5 is an enlarged sectional view of the registering device, and Figs. 6 and 7 are modified forms of the ratchet-wheels.

The improved machine is provided with a box, A, having a central partition, A', which divides the box into two compartments, A² and A³, of equal size. On the top of the box A, in the middle, is located a spout, B, connected in any suitable manner with an elevator, so that the latter discharges the grain from a thrashing-machine or grain-bin into the said spout B. In the spout B is held a gate, C, secured to an oscillating shaft, D, and so arranged that the grain discharged into the top of the spout B can be discharged into either of the compartments A² or A³, according to the position of the said gate C.

In the lower ends of the compartments A² and A³ in the box A are mounted to turn the shafts E and E', carrying the bottoms E² and E³, respectively, provided with side flanges, E⁴ and E⁵, respectively, adapted to pass into slots A⁴, formed on the inner sides of the compartments A² and A³. The bottoms E² and E³, being secured to the shafts E and E', turn with the same and open and close the lower

ends of the said compartments A² and A³. The bottoms E² and E³ are adapted to open alternately upon a gate, F, secured to a shaft, F', mounted to turn in the lower part of the box A, and the said gate F is so arranged as to open alternately into the hoppers G and G', formed on the lower end of the box A and provided with hooks G², on which the bags into which the measured grain is to be filled are hung. The free end of the gate F is adapted to rest alternately on the transverse bars F² and F³, secured in the box A, and on the said bars F² and F³ also rest the lower ends of the swing-bottoms E² and E³, respectively.

On top of the box A is arranged a suitably-constructed frame, A⁵, in which are mounted to turn the shafts H and H', the lower ends of which extend through the top of the box A into the compartments A² and A³. On the inner ends of the shafts H and H' are secured the disks H² and H³, each made of two halves, H⁴, bent in the form of an S, as is plainly shown in Fig. 3. The two halves H⁴ of each disk H² and H³ are placed in opposite directions, so that their bent ends extend up and down, as shown in the said Fig. 3. On the shafts H and H' are secured the gear-wheels J and J', meshing into the intermediate gear-wheels, J² and J³, respectively, which mesh into a central gear-wheel, J⁴, secured to a shaft, J⁵, mounted in suitable bearings in the frame A⁵, and on the other end of the said shaft J⁵ is secured a bevel gear-wheel, J⁶, meshing into a like gear-wheel secured to a shaft on the thrashing-machine, so that the latter imparts a rotary motion to the shafts H and H' while it is at work, and grain is discharged by the elevator into the spout B.

On the shafts H and H' are secured the collars K and K', respectively, between which are held the forked ends of the levers L and L', respectively, fulcrumed at L² on the top of the box A. The levers L and L' extend to the front of the machine, and are pivotally connected by the links N and N', respectively, with the outer ends of the levers O and O', respectively, pivoted on the front of the box A, as shown in Fig. 1. The inner ends of the levers O and O', respectively, are adapted to engage the pins P and P', secured to the vertical bar P², mounted to slide in suitable bearings formed on the front of the box

A. The lower end of the bar P^2 rests on the periphery of a segment, Q, having its fulcrum on the pin Q^2 , secured to the front of the box A. The segment Q is preferably in the shape 5 of a semicircle fastened on a base, Q^3 , in which is the fulcrum Q^2 . In the middle of the semicircle is formed a projection, Q' , the ends of which rest alternately on the side edges of the bar P^2 . The base Q^3 of the segment Q is 10 pivotally connected by a link, D^2 , with a crank-arm, D' , secured on the outer end of the shaft D, which operates the gate C, located in the spout B, so that when the segment Q swings it changes the position of the gate C, whereby 15 the grain entering the spout B is alternately discharged into the respective compartments A^2 and A^3 .

The outer ends of the base Q^3 of the segment Q are pivotally connected by the links 20 Q^4 and Q^5 with the arms Q^6 and Q^7 , secured to the outer ends of the shafts E and E' , which carry the bottoms E^2 and E^3 , before mentioned. On the arms Q^6 and Q^7 are pivoted the downwardly-extending hooks R and 25 R' , adapted to engage the teeth of the ratchet-wheels S and S' , mounted to rotate on suitable studs on the front of the box A.

The ratchet-wheels S and S' are provided on their front faces with the pins S^2 and S^3 , 30 respectively, adapted to engage alternately the lugs T and T' , respectively, secured to the ends of a bar, T^2 , mounted to slide longitudinally in suitable bearings on the front of the box A. The bar T^2 is pivotally connected 35 with the crank-arm F^4 , secured on the outer end of the shaft F', carrying the gate F, above described. The return movement of the ratchet-wheels S and S' is prevented by the pawls S^4 , pivoted to the front of the box A, 40 and engaging the teeth of the said ratchet-wheels.

On the base Q^3 of the segment Q is pivoted a link, U, connected with one end of a lever, U' , pivoted on the front of the box A, and 45 pivotally connected at its other end with an arm, U^2 , adapted to operate the registering mechanism V , secured to the front of the box A, and being of any approved construction.

The operation is as follows: When the device 50 is in the position shown in the drawings, the gate C discharges the grain delivered by the elevator into the compartment A^2 . The grain first falls on the revolving disk H^2 , which throws it against the walls of the compartment A^2 , so that the grain finally falls on the bottom E^2 and accumulates in the said compartment A^2 . When the compartment A^2 is filled with grain, the latter finally extends to the bottom of the disk H^2 and lifts the same 55 so that the lever L is caused to swing, whereby its front end descends and imparts a swinging movement to the lever O by the link N. The lever O, acting on the pin P of the bar P^2 , causes the latter to rise, so that the 60 said bar P^2 disengages the lug Q' of the segment Q. This unlocks the swinging bottom E^2 , so that the weight of the grain accumu-

lated in the compartment A^2 causes said bottom E^2 to swing downward until its lower end rests on the transverse bar F^2 . The downward-swinging movement of the bottom E^2 causes the shaft E to turn so that its arm Q^6 swings downward and causes, by the link Q^4 , a swinging movement of the segment Q in the direction of the arrow a' . The movement of the segment Q causes the arm Q^7 to swing upward, so that the shaft E' is turned and carries its bottom E^3 upward and against the lower end of the compartment A^3 , which is 70 then closed. At the same time the swinging movement of the segment Q causes a downward movement of the link D^2 , connected with the crank-arm D' , so that the shaft D, carrying the said crank-arm, is turned likewise, and the position of the gate C is changed, so that 75 the grain passing into the spout B is now discharged into the compartment A^3 . The upward-swinging movement of the arm Q^7 causes its hook R' to turn the ratchet-wheel S' the distance between one tooth, and the downward movement of the arm Q^6 causes its hook R to move downward and engage the corresponding lower tooth of the ratchet-wheel S, so that at the next upward movement of the said arm Q^6 the disk S is turned the distance of one 80 tooth. Thus it will be seen that by the alternate upward movement of the arms Q^6 and Q^7 the ratchet-wheels S and S' are turned so that finally the pins S^2 and S^3 actuate the bar T^2 alternately by means of the lugs T and T' , so 85 that the position of the gate F is changed, and the grain discharged from the compartments F^2 and F^3 passes on the gate F and alternately into the hoppers G and G' , discharging into the bags to be filled. Now, if the amount of 90 grain necessary to fill the compartments A^2 and A^3 is half a bushel and the ratchet-wheels S and S' have each four teeth, then it requires 95 the compartments A^2 and A^3 to be emptied four times before a change of position of the 100 gate F takes place. If the ratchet-wheels S and S' are each provided with only three teeth, as shown in Fig. 6, then a change of position of the gate F takes place for every three 105 emptyings of the compartments A^2 and A^3 . 110 It is understood that when the position of the gate C is changed the same operation takes place in the other compartment, A^3 , as above described in reference to the compartment A^2 . 115

When one compartment, A^2 or A^3 , is emptied of its contents, as above described, the weight of its respective disk H^2 or H^3 causes its shaft H or H' to descend again. As the grain in the other compartment passes onto the respective disk in the said compartment, the shaft of the said disk is caused to slide downward and the arm P^2 passes down again onto the periphery of the segment Q. Thus the position of the disks H^2 and H^3 and their respective connections with the bar P^2 become 120 normal soon after the respective bottom E^2 or E^3 opens and discharges the grain. The swinging movement of the segment Q imparts a swinging motion to the lever U' by the link 125 130

U, and the lever U', connected by the arm U² with the registering device V, causes the latter to operate, so that the emptying of the compartments A² and A³ is constantly recorded in the usual manner.

Having thus described my invention, what I claim as new, and desire to secure by Letters Patent, is—

1. In a grain measuring and registering machine, the combination, with a box provided with two compartments and swinging bottoms held in the said compartments, of arms operated by the said swinging bottoms, hooks pivoted on the said arms, ratchet-wheels operated by the said hooks, a longitudinal bar receiving a sliding motion by the said ratchet-wheels, a shaft receiving a turning movement by the said bar, and a gate secured on the said shaft and onto which open the said swinging bottoms, substantially as shown and described.
2. In a grain measuring and registering machine, the combination, with a box provided with two compartments and swinging bottoms held in the said compartments, of arms operated by the said swinging bottoms, hooks pivoted on the said arms, ratchet-wheels operated by the said hooks, a longitudinal bar re-

ceiving a sliding motion by the said ratchet-wheels, a shaft receiving a turning movement 30 by the said bar, and a gate secured on the said shaft and onto which open the said swinging bottoms, and hoppers located below the said swinging bottoms and carrying the bags to be filled, the said gate opening alternately 35 in the said hoppers, substantially as shown and described.

3. In a grain measuring and registering device, the combination, with two hoppers and a gate secured to a shaft and opening alternately into the said two hoppers, of a crank-arm secured in the said gate-shaft, a longitudinally-sliding bar pivotally connected with said crank-arm, lugs projecting from the said bar, and ratchet-wheels having a turning 40 movement and each provided with a pin operating on the said lugs so as to impart an alternate forward and backward sliding movement to the said bar to change the position of the said gate, substantially as shown and de- 45 scribed.
